UNITED STATES PATENT OFFICE.

ALFRED R. MORRILL, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

INSEAM-SEWING MACHINE.

Application filed November 15, 1919. Serial No. 338,184.

The invention relates to inseam sewing machines such as are used to sew the upper to the sole of a turn shoe, or to sew a welt and upper to the inner sole of a welt shoe.

5 In welt and turn sewing machines heretofore in commercial use the needle path is at one side of the channel guide about which the shoe is swung in sewing about the toe and since, in sewing about a pointed toe, the 10 channel guide substantially fills the space within the channel for several stitches the successive needle holes are likely to intersect at, or near, the channel side of the between substance and to so weaken it that the stitches 15 are loose and insecure. This is particularly objectionable in sewing turn shoes since the strain incident to turning the shoe causes the stitches to pull away from the sole at the weakened point or points.

20 The present invention remedies this defect in the operation of the prior machines by the provision of a channel guide, which is slotted, or divided, to form two work engaging fingers, which continuously engage the channel and control the position of the shoe, and which are arranged to permit the passage of the needle between them during its work piercing stroke. Although in sewing the toe the guide substantially fills the space within 25 the channel the needle passes through instead of to one side of the guide and as the shoe is turned about the guide the path of the needle during each work piercing stroke may be in a line passing approximately through 30 the center of curvature of the toe so that the successive needle holes will be substantially radial to the curvature of the between substance and thus distributed in a manner to 35 give maximum strength to the seam.

40 The invention may be embodied in machines in which the feed of the shoe is secured in any desired or well known manner and in case it is embodied in a construction in which the channel guide reciprocates in the 45 line of feed the guide should be back fed while the needle is out of the work so that the needle will not interfere with the backward movement of the guide and so that the shoe may accompany the guide in its backward movement in sewing about extremely pointed shoes.

The invention will be readily understood from an inspection of the accompanying

drawings and the following detailed description of the mechanism illustrated therein.

55 In the drawings Fig. 1 is a side elevation showing so much of a welt and turn sewing machine as is necessary to illustrate the application of the present invention thereto. Figs. 2, 3 and 4 are detailed views showing 60 a preferred form of channel guide on an enlarged scale. Fig. 5 is a front elevation of the machine shown in Fig. 1, certain parts being removed to better show the construction behind them. Figs. 6 to 11 are diagrammatic 65 views illustrating the mode of operation in sewing about a pointed toe, and Figs. 12 to 15 are views illustrating the mode of operation of the stitch-forming mechanism and particularly of the preferred form of channel 70 guide.

In the drawings the invention is shown embodied in a welt and turn sewing machine similar in general construction and mode of operation to the machine which is fully 75 shown and described in application No. 260,419, filed October 31, 1918, and in which the work guiding and stitch-forming devices are so mounted and actuated that the feed of the work is continuous during the sewing.

80 This machine is provided with a curved hook needle 2, a looper 4, a thread finger 6, a back gage 8, which, as shown, also acts as a welt guide, a take-up 10 and an auxiliary take-up 12, all of which are similar in construction to the corresponding parts in the machines of Patents No. 1,076,201, October 21, 1913 and No. 1,108,560, August 25, 1914.

85 The machine is also provided with a channel guide in the form of a small roll 14 and the needle, channel guide, and back gage are all reciprocated in the line of feed and are timed to impart a continuous feed to the work during the sewing.

90 The needle and the channel guide roll are 95 mounted on a slide 16, which is similar in construction to the feed slide of the above patents, and is reciprocated by a cam lever 18 engaging a feed cam on the cam shaft. The needle carrying segment is pivotally mounted 100 and guided in a supporting plate 22, projecting downward from the slide 16, and is connected to an actuating lever 24 by a link 26. The channel guide roll is carried on the lower 105 end of a shaft 28, which is mounted in a bearing bracket 30, secured to the slide 16, and the

upper end of the shaft is connected through gearing 32 with a worm on the cam shaft. The gearing and worm are so proportioned that they will not transmit any rotary motion 5 to the channel guide roll during its forward travel, but will rotate it during its backward travel at a speed tending to impart a forward feed to the work.

The swinging arm 36, which carries the 10 back gage, is mounted on a supporting plate 38 secured to a rod 40, which is mounted to slide lengthwise in bearings in the machine frame and also forms the supporting stud on which the slide 16 is mounted. The upper end 15 of the arm is supported on a sleeve 42, which is clamped in a bearing in the plate 38 and surrounds and slides on a fixed stud 44. The arm is connected to the usual back gage slide, which is operated and locked at proper intervals 20 by mechanism similar to that of the above patents. The rod 40 is reciprocated to move the back gage in the line of feed by a cam lever 46, the forward end of which is pivoted to a fixed bracket 48, and the rear end 25 of which carries a roll engaging the feed cam. The lever is connected to the rod 40 by a pivot stud 50 engaging a pivot block which fits within a slot in the enlarged end 52 of the rod.

The parts are so timed that the back gage 30 is back-fed, while the work is being advanced in the line of feed by the needle and channel guide, and the needle and channel guide are back fed while the needle is out of the work and the back gage is advancing in the line of feed, the channel guide rotating during its back feed to assist the back gage in advancing the work.

In embodying the invention in this machine the channel guide roll is slotted, or divided, at its lower end, to provide two rigidly connected fingers 54, which are continuously in engagement with the channel and are so arranged that they will be at substantially equal distances from and close to the opposite sides of the needle path when the needle advances through the between substance.

Since the roll rotates during its back feed each work-engaging finger is preferably rounded off, as indicated at 56, on the side 50 which faces away from the channel when the finger is on the seam side of the needle path. This permits the thread from the needle to the preceding stitch to readily draw under the finger and tightly against the bottom 55 of the channel as the needle draws its loop outward through the work from the position indicated in Fig. 12 to its full retracted position indicated in Fig. 13. It also permits the finger to readily ride over the thread leading 60 from the last needle hole to the looper as the channel guide rotates during its back feed, as indicated in Fig. 14. During its back feed the roll makes a half revolution so that the space between the work-engaging fingers 65 again faces the channel at the completion of

the back feed and thereafter the roll remains in this position during its forward feed and until the needle has again advanced between the fingers and has retracted to draw a new loop through the work.

The advantages of the above construction in sewing about a pointed toe will be apparent upon a comparison of the mode of operation indicated in Figs. 6 to 8 with the mode of operation indicated in Figs. 9 to 11. 70 Figs. 6 to 8 indicate the arrangement of the needle holes and stitches incident to swinging a shoe about a channel guide, which is at one side of the needle path, while Figs. 9 to 11 are similar views indicating the arrangement of needle holes and stitches which may be secured by swinging the shoe about a divided, or slotted, channel guide, which continuously engages and positions the channel while sewing about the toe. For the purposes of comparison a channel guide roll is shown in Figs. 6 to 8 and it is assumed that the roll reciprocates in the line of feed and back feeds while the needle is out of the work. It will be noted that in Figs. 6, 7 and 80 8 the channel guide practically fills the space within the channel and that since the needle must pass to one side of the channel guide the first and second needle holes formed in swinging about the toe pass through the between substance at an undesirable angle and intersect so that comparatively little between substance will be embraced within the thread of the stitch joining the holes. It is also evident, from an inspection of these views, 90 that the arrangement and distribution of the stitches about the toe is not desirable or tended to secure a satisfactory seam. With the construction and mode of operation indicated in Figs. 9 to 11 the channel guide again 100 fills the space within the channel but, in this case, the needle passes through, instead of to one side of, the guide so that the needle holes may be substantially radial to the curvature of the between substance and may be so distributed that the thread of each stitch 110 will embrace sufficient between substance to securely hold the parts together when the seam is subjected to the strains incident to subsequent operations on the shoe.

While it is preferred to employ the specific construction and arrangement of parts shown and described in embodying the invention in the machine of the application above referred to it will be understood that this construction and arrangement is not essential to the broader features of the invention and may be varied, or modified, as found desirable or best suited to the specific construction and mode of operation of the stitch-forming and work-feeding devices of the machine in which it is to be embodied.

What is claimed is:

1. An inseam sewing machine having, in combination, a hook needle, a looper, and a 130

- channel guide having two rigidly connected work-engaging fingers spaced for the passage of the needle and maintained in fixed relation thereto while it is between them.
5. 2. An inseam sewing machine having, in combination, a hook needle mounted to enter the work from the outside, a looper, and a channel guide having two rigidly connected work-engaging fingers spaced for the passage 10 of the needle and maintained in fixed relation thereto while it is between them.
3. An inseam sewing machine having, in combination, a hook needle, a looper, a channel guide having two work-engaging fingers 15 spaced for the passage of the needle between them, and mechanism for reciprocating the channel guide in the line of feed, timed to back feed it while the needle is out of the work.
20. 4. An inseam sewing machine having, in combination, a hook needle mounted to enter the work from the outside, a looper, and a channel guide having two work-engaging fingers spaced to permit the passage of the 25 needle and mounted to remain permanently

within the channel during the sewing and in fixed relation to the needle while it is between them.

5. An inseam sewing machine having, in combination, a hook needle, a looper, a channel guide roll slotted for the passage of the needle therethrough, and means for rotating the roll between successive needle thrusts and stopping it with the slot facing the channel. 30

6. An inseam sewing machine having, in combination, a hook needle, a looper, a channel guide roll slotted for the passage of the needle therethrough and means for reciprocating the roll in the line of feed and for rotating it during its back feed to re-position 40 the slot for the succeeding stroke of the needle.

7. An inseam sewing machine having, in combination, a hook needle, a looper, and a channel guide roll comprising work-engaging 45 fingers spaced for the passage of the needle between them and each rounded on one side to direct the thread under the finger.

ALFRED R. MORRILL.
